UNITED STATES PATENT OFFICE.

ARTHUR C. ROWLEY, OF PHILADELPHIA, PENNSYLVANIA, ASSIGNOR TO GLOBE
AUTOMATIC SPRINKLER COMPANY, OF PHILADELPHIA, PENNSYLVANIA, A
CORPORATION OF PENNSYLVANIA.

DRY-PIPE VALVE.

1,331,383.

Specification of Letters Patent. Patented Feb. 17, 1920.

Application filed September 14, 1918. Serial No. 254,129.

To all whom it may concern:

Be it known that I, ARTHUR C. ROWLEY, a citizen of the United States, residing in Philadelphia, Pennsylvania, have invented 5
5 Dry-Pipe Valves, of which the following is a specification.

One object of this invention is to provide 10 a dry pipe valve of the general type commonly required in automatic sprinkler systems which while being of the maximum simplicity of construction, shall be substantial, certain in action and have its parts so arranged as to permit flow of water in a straight line through its casing without ob- 15 struction.

It is further desired to provide a dry pipe valve including a controlling air clapper or valve and a device which will prevent the reseating of said valve after it has moved a 20 predetermined distance away from its seat in order to insure the opening of the main water valve or clapper:—the invention also 25 contemplating a novel pivotal connection between said clapper and the casing designed to permit of the convenient removal of the former, without requiring the removal of the pivot.

These objects and other advantageous ends I attain as hereinafter set forth, reference 30 being had to the accompanying drawings, in which,

Figure 1 is a transverse vertical section of a dry pipe valve constructed in accordance with my invention; and

35 Figs. 2 and 3 are oppositely viewed vertical sections on the lines 2—2 and 3—3 respectively, Fig. 1.

In the above drawings 1 represents a hollow casting having an inlet 2 for connection 40 to a water supply main and an outlet 3 for connection to the riser of a sprinkler system. The interior of the casing 1 is divided by a partition 4 into a main chamber 5 and an outlet chamber 6, the latter having an ex- 45 tension 7 provided with an opening normally closed by a cover plate 8. A single side plate 9, shown in dotted lines in Fig. 1, closes two side openings into the chambers 5 and 6.

In that part of the partition 4 between the 50 chambers 5 and 6 is mounted a valve seat 10 axially in line with the inlet 2 and outlet 3 and there is a second valve seat 11 mounted between the inlet 2 and the chamber 5 also

axially in line with said inlet and the outlet. A main air valve or clapper 12 is pivotally 55 mounted in the chamber 6 to coact with the seat 10 and a water valve 13 is pivotally mounted or hinged in the chamber 5 in position to coact with the seat 11. For this purpose said valve is connected to an arm 60 14 by a headed stud 16 which projects into a recess in the valve, where it is confined by a plate 17 in such manner as to permit of a slight universal movement of said valve on the arm whereby the former is left free to 65 adjust itself to the seat. Said arm is pivoted to the casing by a spindle or equivalent device 15.

Mounted in a part of the partition 4 which is inclined to the axial line of the inlet and outlet, is a second valve seat 18 set in an opening from the chamber 5 into the extension 7 of the chamber 6, immediately under the cover plate 8 which is bolted to a face of the casing lying in a plane at about 60° 75 to the vertical line of the inlet and outlet.

The controlling air valve 19 has projections or arms 20 forked at their ends to engage two pins 20 projecting into the extension 7 whereby it is hinged or pivoted in 80 position to coact with the valve seat 18. Said valve has projecting from its face into the chamber 5 a lug 21 to which is pivoted or fulcrumed a lever 22 preferably of the first order, one of whose arms is branched 85 and has a cross piece 23 extending between its branches in position to be engaged by the free end of the arm 14 to which the valve 13 is attached. The second arm of the lever 22 coacts with a headed stud 24 set in a projection 25 within the chamber 5 of the casing, and the arrangement is such that said stud or abutment acts as a fulcrum for the lever 22 when the valve 13 and arm 14 act 90 on the cross member 23.

In order that there may be a certain amount of lost motion or yield between the valves 13 and 19, the latter is provided with an annular, more or less yielding face 27, clamped to it by a ring 28 and coacting with the valve seat 18. In order that the valve 19, when raised more than a predetermined distance off of its seat 18 shall be prevented from again engaging the same, I pivot to the top part of the ring 18 a latch in the form 100 of a weighted lever 29, one of whose arms

engages the flange of the valve seat so as to hold its other and weighted arm elevated from its normal position as long as the face ring 27 of the valve 19 engages said seat.

5 If however, said valve turns on its pivots 20 far enough to allow the short arm of the lever 29 to clear the flange of the valve seat 18, the weighted arm will swing into such a position that the first arm will thereafter 10 engage the flange and prevent the valve from seating.

Under conditions of operation, air or other fluid under pressure is introduced into the chamber 6 through the discharge opening 3 15 or through an opening 30. Since the main air valve 12 and the controlling air valve 19 tend to remain on their seats under the action of gravity, this fluid under pressure acts to retain them in their seated positions, 20 and if the water valve 13 be closed, it will be retained in such position against the action of water under pressure in the inlet 2 by reason of the engagement of its arm 14 by the cross bar of the lever 23.

25 As will be understood by those skilled in the art, the area of the controlling air valve 19 acted on by the fluid under pressure in the chamber 6 and the extension 7 will be properly proportioned to normally resist 30 the force exerted on the valve 13 by the water under pressure in the inlet 2. If however, the fluid pressure in the chamber 6 be reduced beyond a predetermined point, the valve or clapper 19 is unseated, thereby permitting 35 the cross bar 23 of the lever 22 to release the arm 14 of the water valve 13. Said valve is then free to open under the pressure of the water, which enters the chamber 5 and swinging the valve 12 on its 40 pivot, flows into the chamber 6, from whence it passes into the sprinkler system through the outlet 3.

It is to be noted that by reason of the peculiar hinge construction between the controlling air valve and the casing, the former is properly positioned on its seat and is free to swing away from the same when the pressure upon it falls to a predetermined point. In addition, when the cover plate 8 45 is removed, it is possible to quickly remove the valve bodily from the casing by disengaging its arms 20^a from their pivot pins 20, in order to permit cleaning or inspection of the seat 18 or of the interior of the casing.

50 55 I claim:

1. The combination in a dry pipe valve of a casing; main air and water valves therein; a controlling air valve; a lever

fulcrumed to the latter valve and having a bearing on part of the casing; with an arm 60 connected to the water valve and hinged to the casing in position to directly engage said lever to hold the water valve closed as long as the controlling air valve remains closed.

2. The combination in a dry pipe valve 65 of a casing; main air and water valves therein; a controlling air valve; an arm hinged to the casing and connected to the water valve; with a lever pivoted to the controlling air valve and placed to engage the 70 hinged arm in position to normally retain the water valve closed, said lever also loosely engaging the casing.

3. The combination in a dry pipe valve of a casing; main air and water valves therein; 75 a controlling air valve; an arm hinged to the casing and connected to the water valve; with a lever pivoted to the controlling air valve and placed to engage the hinged arm in position to normally retain the water 80 valve closed; and a projection within the casing loosely engaged by the second arm of said lever.

4. The combination in a dry pipe valve 85 of a casing having an inlet and an outlet and provided with an opening having a normally closed cover; a partition in the casing dividing it into chambers; valve seats in the partition; a pivot pin projecting into one of the chambers; a controlling air valve for 90 one of said seats including an open bearing for said pivot pin and removable through said opening in the casing; main water and air valves respectively controlling flow through the inlet and the partition; and 95 mechanism operatively connecting the water valve with the controlling air valve.

5. The combination in a dry pipe valve 100 of a casing having an inlet and an outlet and provided with an opening having a normally closed cover; a partition in the casing dividing it into chambers; valve seats in the partition; pivot pins projecting into one of the chambers from opposite sides thereof; a controlling valve for one of said seats including arms having open bearings for said pivot pins, said valve being removable through said opening in the casing; main water and air valves respectively controlling flow through the inlet and through the partition; and mechanism operatively connecting the water valve with the controlling air 105 valve.

In witness whereof I affix my signature.

ARTHUR C. ROWLEY.
